Primary Examiner — T Chase Nelson*Assistant Examiner* — Jeff Lenard D Torres(74) *Attorney, Agent, or Firm* — Banner & Witcoff, Ltd.**CLAIM**

The ornamental design for a shoe, as shown and described.

DESCRIPTION

FIG. 1 is a bottom rear perspective view of a shoe showing my new design;

FIG. 2 is a bottom view thereof; and,

FIG. 3 is a bottom front perspective view thereof. The broken lines and unshaded areas depicting the remainder of the shoe form no part of the claimed design.
